FREEZING APPARATUS

Pasquale Amerio, Hasbrouck Heights, N. J.

Application March 9, 1950, Serial No. 148,657

1 Claim. (Cl. 62—114)

1

This application is a continuation-in-part of my co-pending application Serial No. 87,689, filed April 15, 1949, now abandoned.

This invention relates to commercial freezing apparatus and relates more particularly to an improved freezer of the type which has plural spaced plates which are arranged to move into intimate engagement with the containers holding the products being frozen and to exert a measured degree of pressure on the products.

An important object of the invention is to provide an improved arrangement for exerting pressure on one of the terminal plates in a bank of such plates, the other terminal plate being fixed.

A further object of the invention is to provide a novel suspension arrangement for all of the plates, except the lowermost plate which is fixed, in an assembly wherein the plates are arranged in superimposed relation and pressure is applied to the top plate, which in turn is applied to the packaged articles of food in the area between the several lower plates.

Yet another object of the invention is to provide an improved header arrangement for feeding the fluid refrigerant to the hollow plates so as to avoid the formation of bubbles at the inlet port which tend to obstruct the free flow of fluid and thus cause uneven and uncertain freezing results. The improvement in this connection consists of a vertical feed duct extending downwardly through the refrigeration chamber and terminating in a horizontal section extending across a portion of the lower wall of said chamber. A plurality of vertical ducts of progressively increasing lengths extend upwardly from the horizontal section, the upper ends thereof being connected with the inlet ports of the hollow plates by flexible ducts, also of progressively increasing lengths. By this arrangement the fluid refrigerant flows down to the horizontal duct and then rises in the vertical ducts. There is no formation of bubbles at the inlet ports and the result is uniform freezing of all packages in the chamber.

In the drawing:

Fig. 1 is a movable plate freezer embodying the present invention, the view showing the doors in open position.

Fig. 2 is a broken side elevation of the several plates showing the suspension arrangement.

Fig. 3 is a rear elevation of the plates showing the header assembly constituting the improved fluid feed.

Fig. 4 is a horizontal section taken on line 4—4

50 55 gish circulation. Flexible ducts 38 connect the

2

of Fig. 3 showing the placement of the inlet and outlet flexible ducts.

The freezing apparatus includes an insulated housing 10 having front doors 11 and 12 and a plurality of movable hollow plates 13 which receive the fluid refrigerant. The lowermost plate 14 is fixed and is supported at its two opposed transverse edges on angle brackets 15 secured to spaced vertical posts 16 on each side of the refrigeration chamber 17.

No details of the construction of the hollow plates 13 and 14 are shown since plates of this character are well known in the art. The uppermost movable plate 13' is provided on its upper surface with a reinforcing member 21 and is supported by a piston rod 22 extending into a hydraulic jack 23. For the purpose of guiding plates 13 in their up and down movement they are provided with spaced pins 24 extending transversely at each end of the plates, such pins engaging the inner surface of posts 16.

Each movable plate 13 is reinforced along each lateral edge by an angle bracket 26 which may be welded thereto and pins 24 may be welded to the bracket or directly to the plate. The plate 13 immediately below plate 13' is suspended from the latter by plural bolts 27 having a head 28 at one end thereof and carrying a nut 29 at its opposite end. One such bolt may be positioned adjacent each corner of the plates, the bolt hole passing through the angle 26. Thus, the plate 13 may become spaced relative to 13' a distance equal to the distance between the head and the nut.

The next lower plate is suspended from the plate next above in the same fashion, the bolt below being conveniently staggered as shown in Fig. 2.

The fluid refrigerant is supplied to the plates by means of a vertical supply duct 34 which at its upper end is connected with the compressor 34'. At its lower end the supply duct has a short horizontal square section 35 and a plurality of vertical ducts of smaller diameter than ducts 36 and 37 extending upwardly from section 35, such ducts being of progressively increasing length ranging from duct 36, which is the shortest, to duct 37 which is the longest and which is disposed alongside of vertical duct 34. Square duct 35 has at the end thereof a bleed valve 35' which is provided for the drainage of the undesirable oils that normally accumulate in freezing systems of this type. The undesirable oils being heavier than the refrigerant fluid settle in duct 35 and do not enter the plates 13 thus causing sluggish circulation. Flexible ducts 38 connect the

outlet ends of ducts 36-37 with the inlet ports 39 of plates 13, such flexible ducts also being of progressively increasing lengths.

The lengths of fixed ducts 36-37 and flexible ducts 38 are so proportioned as to permit plates 13 to move from their upper and lower extreme positions without any tugging on the flexible ducts.

The plates are also provided with outlet ports 40 which are disposed on one side thereof, Fig. 4, 10 and which are connected to flexible ducts 41. The ducts 41 are in turn connected to a return duct 42 which returns the fluid refrigerant, now in its gaseous state, to the compressor.

The flexible ducts 41 are positioned on one 15 side of the plates as shown in Fig. 4 and are similarly proportioned to provide freedom of movement of the plates 13.

In operation the uppermost plate 13' is first raised by the hydraulic jack to its uppermost position and in so doing the several lower plates 13 are spaced apart their maximum distance as defined by the lengths of bolts 27. The articles to be frozen, in packaged state, are placed on the upper surfaces of the several plates and the piston then moved downwardly to apply a desired pressure on the packaged foods. The pressure is uniformly transferred to all of the packages and the freezing operation then commences. The liquid refrigerant passes downwardly through supply duct 34, into horizontal section 35 and thence upwardly through the vertical ducts 36-37 in an even flow into the hollow plates.

While one form or embodiment of the invention has been shown and described herein for illustrative purposes, and the construction and arrangement incidental to a specific application thereof have been disclosed and discussed in detail, it is to be understood that the invention is limited neither to the mere details or relative 40 arrangement of parts, nor to its specific embodiment shown herein, but that extensive deviations from the illustrated form or embodiment of the

invention may be made without departing from the principles thereof.

The embodiments of the invention in which an exclusive property or privilege is claimed are defined as follows:

In a freezing apparatus, the combination of a housing, a plurality of hollow plates provided with inlet and outlet ports for receiving a fluid refrigerant and arranged in superimposed relation, a vertical duct extending downwardly through the housing for supplying the fluid refrigerant and terminating in a horizontal section provided with a bleed valve at its outer end, a plurality of vertical ducts of progressively increasing lengths leading upwardly from said horizontal section, and flexible ducts of progressively increasing lengths connecting the upper ends of the vertical ducts with the inlet ports disposed at the rear of said plates, a vertical return duct, progressively increasing lengths of flexible ducts connecting said outlet ports with said return duct disposed at one side of said plates, the lower plate being fixed and the upper plate being movable toward and away from the lower plate, and means comprising headed bolts for suspending each adjoining pair of movable plates successively from the upper plate, the bolts being slidable relative to the plates to permit the movable plates to assume contact with articles placed between the plates.

PASQUALE AMERIO.
